UNITED STATES PATENT OFFICE.

JOHN E. HOVENDICK, OF DESOTO TOWNSHIP, WASHINGTON COUNTY, NEBRASKA.

HOIST.

No. 888,612.

Specification of Letters Patent.

Patented May 26, 1908.

Application filed September 10, 1907. Serial No. 392,191.

To all whom it may concern:

Be it known that I, JOHN E. HOVENDICK, citizen of the United States, residing in De-
soto township, in the county of Washington
5 and State of Nebraska, have invented certain
new and useful Improvements in Hoists, of
which the following is a specification.

My invention relates to hoisting devices in
which a winding-drum operates in conjunc-
10 tion with a connected cable to raise and lower
anything vertically movable; and the objects
of my improvement are, first, to provide a
hand-operated hoist having its moving parts
compactly assembled in a frame adapted to
15 be fastened to and between the upright tim-
bers of a substructure to support it in posi-
tion for use and where it will be housed out
of the way; second, to provide a hoist of the
character described that may be operated
20 from either side of said supporting substruc-
ture; and, third, to provide a hoist of this
kind that will be automatically and safely
locked at any point at which its operation is
stopped. I attain these objects by the mech-
25 anism illustrated in the accompanying draw-
ing, in which—

Figure 1 is an outside elevation of my
whole contrivance applied to the end of a
30 barn, part of the inclosing wall of which is
broken away to reveal the assembled mechan-
ism; Fig. 2, a vertical section of the wall re-
vealing a side elevation of the mechanism;
Fig. 3, is an inside elevation, at larger scale,
35 of the castiron frame of the hoisting mechan-
ism with the moving parts removed; and
Fig. 4, a like side elevation of said frame
alone.

Similar numerals refer to similar parts
throughout the several views.

40 The contrivance is shown applied to a barn
having a lower door 9 directly below the gable
opening 8. The door closure 3 slides verti-
cally in the ways 4, and 4 on the end 2 of the
barn and is limited in movement by the
45 blocks 6, and 6 and the cornice 5 and is oper-
ated by a cable 14 which has one end 14''
fastened centrally to the lower end of the
closure. The adjacent end portion 14' ex-
tends upward between the door and siding, or
50 if the door hangs close, in the vertical groove
15 in the face of the siding; it runs up over
the grooved pulley 11 fastened to the under-
side of the door-sill, thence down under a
like pulley 12 fastened in the stud-space of
55 the wall, then making a lateral run to and

over the pulley 13, to clear the door 9, thence,
downward with its other end fastened to the
winding-drum 18.

The winding-drum has at one end the gear
or worm-wheel 19, preferably an integral 60
part of the drum, or mounted concentrically
to revolve with it on the shaft 22 journaled in
the frame 16. A worm 25 is mounted on the
shaft 24,—or preferably the worm is an inte-
gral part of the shaft. This worm-shaft is 65
journaled at right angles to the drum-shaft in
the open boxes 20, 20, to bring the worm into
engagement with the gear to revolve the
drum. The shaft 24 is fitted for the crank 26
on either end, either outside or inside of the 70
building..

The hoisting gear frame consists of an
integral hook-shaped casting, having a longer
downward projecting leg or base part 16''
connected to the parallel inclined leg 16''' by 75
an angle bar head consisting of the horizon-
tal cross-plate 16 and the pendent flange 16'.
Where the shaft 22 is disposed through, to
carry the winding-drum between said legs
within the hook, the outer surfaces of the 80
base leg 16'' and the point of the hook or leg
16''' have the bosses 17 and 17. These
bosses supply increased bearing for the shaft
22, are close fitted in the adjoining wall-
studs 27 and 28, and with the bolt 21' 85
through the hole 21 at the lower end of the
base leg and the stud 27 securely fasten the
hoist in the wall. The pedestals 20 and 20
for convenience in casting may be made sep-
arately and bolted on. The head cross-plate 90
16 is narrowed away from the side of the
drum receiving the cable, in order to clear
the cable when running at different angles
and to facilitate placing the hoist close up to
the pulley 11, as is sometimes desirable when 95
the pulleys 12 and 13 are omitted and the
hoist placed directly below the door 3, 8; the
flange 16' is widened downward to a line just
clearing the drum and worm-wheel and gives
the connecting head or cross-bar the requi- 100
site strength. By slight modifications this
frame may be made of sheet metal bent from
a properly cut blank. It is obvious that by
a suitable location of pulleys in addition to
pulley 11 the hoist may be located at any 105
desired place about the building.

By the crank the worm is turned to revolve
the drum and wind up the cable to raise and
close the door against its own weight; and a
reverse turning lets the door slide open. The 110

worm-gear holds the door suspended at any desired position in its vertical range of movement.

I claim:

- 5 1. In a hoist the combination of, a hook-shaped frame having bosses adapted to engage corresponding mortises in a supporting structure at the outsides of the point and stem of said hook and perforations in axial 40 alinement through said point and stem and through said bosses and a bolt-hole at the end of said stem to receive a bolt into said supporting structure, a shaft disposed across the hook in said perforations, a cable-wind- 45
- 10 ing-drum and connected worm-wheel mounted on said shaft between the point and stem of said hook, a crank-shaft disposed across the inside of the stem through pedestals thereon, and a worm mounted on said crank- 50
- 15 shaft to engage said worm-wheel.
- 20 2. A hoist comprising a hook-shaped frame, a cable-winding-drum and connected worm-wheel mounted between the point and stem of the hook on a shaft disposed across 55 through said stem and point, the bend of the hook bent laterally away from the cable-receiving side of the drum and bosses on the outsides of the point and stem around the ends of the drum-shaft to serve as attaching 60
- 25 lugs seated in mortises in a substructure to support said hook-shaped frame and a perforation in the end of said stem to receive an attaching bolt into said supporting sub- 65
- 30 structure, a crank-shaft boxed on the stem of the hook, and a worm mounted on the crank-shaft to engage said worm-wheel.
- 35 3. A frame for a hoist, consisting of, a long leg and a short leg disposed in parallel planes from the opposite ends of a connecting cross- 70

bar, said legs having perforations in axial 40 alinement to receive a shaft across to carry a cable-winding-drum and connected worm-wheel between said legs, bosses on the outsides of said legs around said perforations to increase the bearings of the shaft therein and 45 provide the frame with attaching lugs adapted to be seated in corresponding mortises in a supporting structure, said long leg perforated at its projecting end to receive a bolt to fasten the leg to said supporting structure, and boxes on said long leg adapted to receive a shaft carrying a worm to engage 50 said worm-wheel.

4. A frame for a hoist, consisting of, a long leg and a short leg disposed in parallel planes 55 from opposite ends of a connecting cross-bar, said legs having perforations in axial alinement to receive a shaft across to carry a cable-winding-drum and connected worm-wheel between said legs, said connecting- 60 cross-bar narrower than said legs and disposed toward that edge of said legs opposite to the cable-receiving side of said drum, bosses on the outsides of said legs around 65 said perforations to increase the bearings of the shaft therein and provide the frame with attaching lugs adapted to be seated in corresponding mortises in a supporting structure, said long leg having a hole to receive a bolt into said supporting structure, and boxes on 70 said long leg adapted to receive a shaft carrying a worm to engage said worm-wheel.

In testimony whereof I affix my signature in presence of two witnesses.

JOHN E. HOVENDICK.
